FASTENER DRIVING TOOL

Allen R. Obergfell, Park Ridge, and Frank R. Potucek
and Andrew L. Yohana, Des Plaines, Ill., assignors to
Duo-Fast Corporation

Filed Apr. 29, 1974, Ser. No. 464,910

Term of patent 14 years

Int. Cl. D8—05

U.S. Cl. D8—70

FIG. 1 is a side view of a fastener driving tool embodying our new design;

FIG. 2 is a top view of the tool;

FIG. 3 is a front view of the tool;

FIG. 4 is a side view of the tool showing the side opposite to that shown in FIG. 1;

FIG. 5 is a bottom view of the tool; and

FIG. 6 is a rear view of the tool.

The broken line showing of a portable power tool is for illustrative purposes only.

We claim:

The ornamental design for a fastener driving tool, substantially as shown and described.
